UNITED STATES PATENT OFFICE.

SOLOMON R. SHEAKLEY, OF BRADFORD, PENNSYLVANIA.

OIL-WELL RIG.

SPECIFICATION forming part of Letters Patent No. 499,045, dated June 6, 1893.

Application filed October 29, 1892. Serial No. 450,863. (No model.)

To all whom it may concern:

Be it known that I, SOLOMON R. SHEAKLEY, of Bradford, in the county of McKean and State of Pennsylvania, have invented certain new and useful Improvements in Oil-Well Rigs; and I do hereby declare the following to be a full, clear, and exact description of the invention, such as will enable others skilled in the art to which it pertains to make and use it, reference being had to the accompanying drawings, which form part of this specification.

My invention relates to an improvement in oil well rigs; and it consists in the novel construction and arrangement of the parts of the derrick and operating mechanisms as will be fully described hereinafter and more especially referred to in the claims.

The object of my invention is to build a rig so as to accommodate within the derrick proper all the mechanical means by which wells of the description named are drilled and operated. This is accomplished by combining with the ordinary derrick a suitable plat- form and suitable blocks upon the floor of the derrick for supporting the engine, and by constructing in a simple and substantial manner a platform upon one of a series of vertically arranged girts, on which platform the band wheel and bull rope pulley are mounted.

A further object of my invention is to construct a new and improved cross head for the pitman which actuates the drill or pump as the case may be.

Referring to the accompanying drawings— Figure 1 is a perspective view of my improved derrick, or rather of the lower portion of the same. Fig. 2 is a vertical cross sectional view of the derrick. Fig. 3 is a detached view of the band wheel, the bull rope pulley and their supporting shaft. Fig. 4 is a view of the cross head and guide therefor detached. Fig. 5 is a sectional view of the same. Fig. 6 is a rear elevation of the slide-way and cross head. Fig. 7 is an elevation of a portion of the derrick showing the cross heads secured between rods W in solid lines, and in its operative position in dotted lines.

The derrick in which I make my novel ar- ranged of machinery and the several operating parts essential to the successful op- eration of a well is in construction very simi-

lar to the ordinary derrick, with the exception that its lower portion is constructed of heavier material than that usually employed, 55 so that a strong foundation is provided for the elevated frame A, which rests on one of a series of girts or tiers B, two or more of the latter being arranged in vertical succession so that the vertical position of the frame A, may 60 be varied to suit the working of the mechanical contrivances presently to be mentioned.

Suitably journaled in the frame A, is the shaft C, and mounted thereon is the band wheel D, connected with the engine E, by the belt F. The engine is substantially mounted as shown on the floor of the derrick. Loosely mounted on the shaft C, is the peripherally grooved pulley G, which may be made rigid with shaft so as to revolve with it by the movable clutch H, of ordinary construction which is operated by the depending lever I, extending within reach of the operator. An endless rope encircles this pulley which extends to the bull wheel J, suitably mounted on one 70 side of the derrick as shown. Through the medium of the belt F, and rope I', the said bull wheel is revolved by the engine and drill rods and other tools are thereby easily elevated into position through the medium of 75 the rope and tackle J', which is actuated by the drum of the said bull wheel.

Arranged within the derrick are the upwardly converging supports L, and secured thereto are the parallel strips M. Confined 85 between these strips is the vertical guide way N, upon which moves the cross head O, which is pivotally connected by means of the vertically extending rod P, to the crank Q, on the end of the shaft C. The said shaft being re- 90 volved through its connection with the engine the said rod P, is actuated and the head O, reciprocated vertically. The guide N, is slotted longitudinally and extending therein from the head O, is the tongue R. This tongue is 95 the same thickness as the guide N, and projecting from the same are the headed projections S.

T, designates a plate having openings U, whereby the plate may be fitted over the said 100 projections and made to bear against the guide N, and as the said openings are constructed with offsets the plate may be pushed down, the said offsets fitting over the projections

but behind the heads thereof so that the plate is securely held in place. As a further precaution against the same becoming displaced a set screw U', is provided which penetrates the plate and extends into the tongue R, thus binding together the latter and the said plate in a most secure manner. From this described construction it will be understood that while the head O, has a free vertical movement yet it is quite impossible for the same to become displaced on the guide N. The head is provided with the outwardly projecting ears V, having grooved upper faces for accommodating any suitable device for grasping the pump rod or drill and the said device is held in place by the caps V'. The head O, reciprocates in a vertical line with the point of operation below so that the same would be in the way of the rope and tackle J, while the latter is operating over the well. To obviate this trouble two rods W, are arranged parallel with each other and held between the cross strips M. These rods are inclined at a suitable angle so as to accommodate the head O, as the latter is swung thereto on the rod P as shown in Fig. 7. The projecting tongue of the head extends between the said rods and the plate T, confines it in place in the manner above described as when adjusted to the guide N. The said rods being at the proper angle or inclination the head may be reciprocated by its pitman and the shaft C, while the latter is transmitting power to the bull wheel for operating the rope and tackle J. When the operation of this last mentioned part has been completed the head may be returned to its position on the guide N, and the drilling or pumping resumed with very little interruption or delay in adjusting the same. As the engine and other machinery, with the exception of a portion of the bull wheel are entirely within the derrick the latter may be boarded up or inclosed either a portion or

the whole length of the same and thus protect the operating parts. The boiler may be located in a convenient position either adjacent the derrick or removed therefrom as may be desired.

Having thus fully described my invention, what I claim as new, and desire to secure by Letters Patent, is—

1. In an oil well rig the combination of a derrick, an engine arranged adjacent to one side thereof, a bull wheel mounted in the opposite side, a rope and tackle operated by the latter, a shaft journaled within the tower, a band wheel thereon for the engine belt, a pulley movable longitudinally on said shaft which is adapted to engage and revolve with the band wheel, an endless rope connecting the pulley and the bull wheel, and a mechanism connected with said shaft for operating a pump or drill, substantially as shown and described.

2. In an oil well rig, the combination of a slide-way, a cross head adapted to move thereon having a depression in its upper end, a pitman rod pivoted at its lower end in said depression, ears V projecting from the head, and a suitable tool operating device loosely secured between said ears, substantially as shown and described.

3. In an oil well rig, the combination of a derrick, a crank shaft journaled therein, a means for operating the same, a vertically sliding head and a guide therefor, a connection between the head and the said shaft, and rods W, arranged as shown in relation to the said head for the purpose described.

In testimony whereof I affix my signature in presence of two witnesses.

SOLOMON R. SHEAKLEY.
